UNITED STATES PATENT OFFICE.

JOHN C. ROGERS, OF ORD, NEBRASKA.

MANURE AND DIRT DUMP.

No. 845,124.

Specification of Letters Patent.

Patented Feb. 26, 1907.

Application filed January 19, 1906. Serial No. 296,743.

To all whom it may concern:

Be it known that I, JOHN C. ROGERS, a citizen of the United States, residing at Ord, in the county of Valley and State of Nebraska, have invented certain new and useful Improvements in Manure and Dirt Dumps, of which the following is a specification.

This invention relates to a new and useful manure and dirt wagon loader, and has for its object to provide an inexpensive, durable, and comparative simple means of this character whereby manure and dirt wagons and the like may be conveniently and expeditiously loaded.

15 A further object of the invention is to provide means whereby the load-carriage may be held in its elevated position for allowing the load thereupon to automatically dump.

The invention consists in the construction and novel combination and arrangement of parts hereinafter fully described, illustrated in the accompanying drawings, and pointed out in the claim hereto appended, it being understood that various changes in the form, proportion, and minor details of construction may be resorted to without departing from the principle or sacrificing any of the advantages of the invention.

In the drawings forming a part of this specification, Figure 1 is a side elevation of a manure and dirt wagon loader constructed in accordance with my invention, showing the load-carriage in both its upper and lower most position and the carriage-supports both in their outer and inner positions. Fig. 2 is a longitudinal or sectional view of Fig. 1. Fig. 3 is an end elevation, showing the hinged members of the load-carriage in their open or downward position. Fig. 4 is a longitudinal sectional view of the load-carriage with one of the hinged members in its open position. Fig. 5 is a transverse sectional view of the load, showing the hinged members open or in their downward position.

45 Similar numerals of reference indicate corresponding parts in all the figures of the drawings.

Referring to the drawings, 1 designates the upright standards or supporting-legs of the rectangular frame A, which may be built of any suitable height and of any suitable material. Secured longitudinally of and to all the legs 1 upon each side of the frame A are the cross or strengthening members 2, 3, and 4. Secured transversely of the frame A and near the top edge of the standards or legs 1 are

the strengthening members 5, which, together with the members 2, 3, and 4, hold the legs 1 in a permanent position, thus making a rigid frame A.

6c

Mounted transversely of the frame A upon the members 2 near the top of the frame are the members 6, which are held in position and braced by means of the brace members 7.

Journalized within the pillow-blocks 8, which are mounted upon the top edge of the members 5 and 6 of the frame A, and near the center thereof, is the shaft 9, which is provided near the center with the windlass 10, which in turn is provided with the projection or 70 brake-fingers 11, which fingers rest upon the stop 12, which is secured to the connecting-rod 13, which at its opposite end is pivotally held to the brake-lever 14, that is pivoted, by means of the pin 15, to the bracket 16, 75 which is secured to one of the intermediate legs or standards 1, as clearly shown in Fig. 3.

The stop 12 is held in position and guided in its reciprocating movement by means of the downwardly and outwardly projecting 80 fingers or guide-pins 17, as clearly shown in Figs. 2 and 3. Fig. 3 discloses the windlass locked by means of the brake, thus preventing the same from rotating in either direction, as the pins 11 will come in engagement 85 with the stop 12.

Secured at one end to the shaft 9 and near the outer sides of the windlass 10 are the chains 18, the duties of which will be more fully described hereinafter.

90

The carriage for loading wagons or the like with manure or dirt will now be described. This carriage comprises a rectangular frame B, consisting of the two triangular side members 19 and the two transverse end members 20. The inner and lower edges of these members 19 and 20, it will be observed, are recessed, as at 21 and 22, so as to form a tight union between the side and end members and outside and end edges of the hinged 100 member C. These members C are hinged to the side members 19 by means of suitable hinges 25, secured to the lower faces of each. The upper face of these hinged members C are provided with slats 24 to strengthen the 105 members and further prevent horses from slipping when filling the carriage with manure and dirt by means of scrapers and the like.

Secured near one end and to each of the outer slats 24 are the screw-eyes 25, to which 110 are connected a pair of short chains 26, which are at their opposite ends connected to the

rings 27. Connected to these rings 27 for the purpose of raising and lowering the carriage B and closing the door or hinged members C are the hooks 28, to which are secured one 5 end of the chains 18, which are at their opposite ends secured to the shaft 9.

The pivotally-held supports for holding the carriage in its elevated position and the means for operating said supports will now 10 be described.

A pair of standards or supporting members 29 are employed at each end of the apparatus and pivoted to the inner side of the corner-legs 1 by means of the pins 30'. Secured to the top of these supports or standards 29 and transverse of the frame A are the cross supporting members 30, which project beyond the members 29, as at 32, and engage the outer end faces of the corner-leg 1 to prevent 20 the extreme inner movement of the supports B' should the lever 33 be carried to a position just opposite that shown in full lines in Fig. 1. Pivoted to the lever 33, which is pivotally held upon one of the intermediate 25 legs 1, and upon each side of the pin 34 are the connecting-rods 35, which are at their opposite ends pivoted to the standard or supporting-legs 29, as clearly shown in Fig. 1. By the reciprocating movement of the lever 33, it will be observed, the supports B' are imparted an outward and inward movement. 30

There is a rope 36, which is wound around the windlass 10 and which passes under a roller 37, pivoted to one of the intermediate 35 legs 1, and further passes under and works upon the roller 38, which is pivoted to the ears 39 of block 40 for the purpose of rotating the shaft 9, thus causing the chains 18 to wind thereupon and causing the carriage B 40 to rise. The block 40 may be securely held to the ground by any suitable means; but for convenience I have shown stakes in the drawings.

The operating of the device is as follows: 45 After the carriage has been filled by scrapers or the like when in the lowermost position, as disclosed in full lines in Fig. 1 and dotted lines in Fig. 2, the rope 36 is drawn in the direction indicated by arrows, thus causing the windlass 36 to revolve, causing the chains 18 to wind upon shaft 9, thus raising and elevating the carriage B to the position as disclosed in dotted lines in Fig. 1 and full lines in Fig. 2. As the supports B' are in their 50 outward positions, as shown in full lines in Fig. 1 and dotted lines in Fig. 2, when the carriage B is being raised, these supports are, after the carriage has reached its destination, drawn inward by means of the lever 33 55 to the position as shown in dotted lines in Fig. 1 and full lines in Figs. 2 and 3, thus allowing the end extremities of the carriage B

to rest upon the cross members 30 of the supports B'. At the same time the carriage engages the supports B' the rope is slackened, 65 thus allowing the weight of the load upon the hinged member of the carriage B to open downward, thus causing the load to leave the carriage and fill the wagon or receptacle that is to be placed under the carriage. After the 70 load has dumped, the rope 36 is again drawn in the direction of the arrow, causing the hinged member C to close, as shown in Fig. 2. After the members have been closed the rope is drawn a little farther in order to throw the 75 supports B' into their outward position to allow the carriage to be lowered to the ground and again fill. When the carriage is in its lowermost position, the chains 18 are detached from the ring 27 to allow the scrapers 80 or the like to pass over the carriage. The brake is locked while the carriage is in both its lowermost position and in its dumping position, so as to prevent the windlass from revolving and slackening the ropes. 85

Having thus described my invention, what I claim is—

In a device of the class described, the combination with an upright frame and the pivotally-held carriage-supports which are connected at their lower ends to the inner face of the corner-uprights comprising said upright frame, a lever pivotally connected to one of the intermediate uprights, a rod connected at each side of the pivot-point and connected at 90 their opposite ends to one of the pivotally-held carriage-supports on each side of the upright frame, a right-angular vertically-adjustable carriage having a divided hinged bottom connected to the side sills of the carriage, 95 short chains connected to the upper face of the two hinged sections comprising the bottom of said carriage to prevent extreme outward movement thereof, a brake-lever pivoted to the aforesaid intermediate upright, a 100 rod connected to the upper end thereof and at its opposite end to a cross-piece having depending guide-arms, a shaft, chains connected to said shaft and at their opposite ends to the aforesaid short chains midway of 105 their length, a drum secured to said shaft midway of its length and having its periphery provided with projections or pins with which the aforesaid cross-piece is adapted to engage to control the opening and closing of the aforesaid divided hinged bottom and the 110 raising and lowering of the aforesaid vertically-adjustable carriage. 115

In testimony whereof I affix my signature in presence of two witnesses.

JOHN C. ROGERS.
